UNITED STATES PATENT OFFICE.

JOHN D. CARROLL, OF EVANSVILLE, INDIANA, ASSIGNOR TO TURBO ROTARY ENGINE CO., OF EVANSVILLE, INDIANA, A CORPORATION OF SOUTH DAKOTA.

ROTARY ENGINE.

1,342,496.

Specification of Letters Patent.

Patented June 8, 1920.

Application filed October 9, 1916. Serial No. 124,533.

To all whom it may concern:

Be it known that I, JOHN D. CARROLL, a subject of the King of Great Britain, residing at Evansville, in the county of Vanderburg and State of Indiana, have invented 5 certain new and useful Improvements in Rotary Engines, of which the following is a specification.

My invention relates to rotary engines, 10 particularly to that type in which a piston drum is rotatably mounted in a cylinder eccentric therewith, with blades journaled eccentric with reference to the drum and projecting therefrom to contact with the 15 cylinder walls and to shift radially as the drum rotates, the blades together with the cylinder and drum forming working chambers for the expansion of the driving fluid.

Among the important objects of the invention 20 are to provide simplified construction and arrangement which will produce strength and compactness and which will enable the parts to be readily assembled or taken apart; to provide such inter-relation 25 and support of the various parts that smooth and well-balanced operation will result; to provide improved packing means for preventing leakage of driving fluid from the working chambers and to provide arrangement 30 which will equalize the end thrust and keep the rotating drum properly spaced in the cylinder; and to provide construction and arrangement which will enable the engine to be operated by steam or 35 by gases.

On the accompanying drawings a construction involving the above and other features of my invention is shown. In these drawings—

40 Figure 1 is a vertical diametral sectional view of the engine,

Fig. 2 is a sectional view on plane 2—2, Fig. 1,

45 Fig. 3 is a perspective view of one of the blade members,

Fig. 4 is a side view of a section of the cylinder wall showing the arrangement of the packing,

50 Fig. 5 is a sectional view on plane 5—5, Fig. 4, and

Fig. 6 is a sectional view on plane 6—6, Fig. 5.

Referring to the drawings, 10 and 11 designate as a whole similar end structures 55 each comprising the disk-shaped head 12,

the inwardly extending peripheral flange 13 and the flange 14 extending outwardly from the inner ends of the flange 13. Between the end structures is the cylinder 15 having the end flanges 16 and 17 which are secured to 60 the flanges 14 of the side structures by bolts or screws 18. Within the cylinder is the cylindrical drum section 19 integral with and extending from the end plate 20, and the other end plate 21 is centered by the 65 annular tongue 22 and groove 23 on the drum cylinder, and is connected to the latter by through bolts 8. To facilitate drilling of the holes for the bolts and subsequent assembling, one or more dowel-pins 9 (Fig. 70 2) are preferably employed. The plate 20 has the annular boss 24 extending laterally outwardly therefrom and the end plate 21 has a similar boss 25, the bosses extending 75 into the end structures 10 and 11 adjacent the horizontal flanges 13 thereof. The head 12 of the end structure 10 has a cylindrical hub 26 extending centrally inwardly therefrom and between this hub and the annular boss 25 is interposed a ball bearing 27. The 80 head 12 of the end structure 11 has the central horizontal opening 28 which is surrounded by the annular inwardly extending hub 29, and between this hub and the boss 24 is interposed a ball bearing 30, the drum 85 structure being thus mounted within the end structures and cylinder for rotation. A shaft 31 extends centrally through the opening 28 and through the hub 26 and receives the annular hub 32 extending outwardly 90 from the drum structure end plate 20, this hub extending concentrically into the hub 29 and being rigidly secured to the shaft so that the shaft will be rotated with the drum structure. The shaft passes centrally 95 through the end structures 10 and 11 and through the drum structure, but the cylinder 15 is eccentric with reference to the shaft, as clearly shown in Fig. 1.

Extending through the drum eccentric 100 with reference thereto but concentric with the cylinder is the cylindrical bearing boss 33 which may be integral with and forms an eccentric extension of the hub 26, a reduced portion of the shaft 31 extending 105 through this boss and the hub 26. The boss is surrounded by a bushing 34 on which the various blade structures B are journaled. Three such blade structures are shown, each comprising a blade 35 from which eccentric 110

straps or bearing lugs 36 extend. These eccentric straps or lugs are nested compactly on the bushing 34, one of the blade members being shown as having only one strap 36 which is received between the two straps 36 of the second blade member, which straps are in turn received between the straps 36 of the third member, the straps being thus arranged side by side on the bushing with the blades 35 extending substantially radially outwardly. Through the drum 19 and drum plate 20 and its boss 24 are three equally spaced cylindrical bearing passageways 37, and through the drum plate 21 and its boss 25 are opposed bearing passageways 38. Extending through the opposed passageways are the cylindrical bearing rockers 39 each provided between the drum plates 20 and 21 with a diametrically extending slot 40 for passage of the blade 35 of one of the blade members B (Fig. 1). The eccentricity of the various structures is such that these blades will, during rotation of the drum, be reciprocated in the members 39 and such members will have a slight rocking motion on their axes, and the blades will at their outer ends always engage with the inner wall of the cylinder 15, and will travel through the working chamber 41 formed between adjacent blades and the relatively eccentric walls of the cylinder and drum. A fluid inlet 42 extends tangentially to the working chamber and at a diametrically opposite point an exhaust passageway 43 extends from this chamber. Fluid, as for example steam, entering at the inlet 42 will impinge against the blade below the inlet and the drum will be rotated, the blade traveling from the narrower toward the wider section of the working chamber in advance thereof so that the steam behind the blade can expand. As the blades successively pass the fluid inlet the fluid will impinge thereagainst and continuous driving torque will thus be exerted against the blades to rotate the drum. When a blade reaches and passes the exhaust outlet the steam in the chamber behind the blade will exhaust to the atmosphere. It is evident that instead of using steam for the driving fluid gases may be used, and the engine can be readily utilized as an explosive engine.

One of the objects of my invention is to so construct the parts that the engine can be readily assembled or taken apart. In general, the construction and arrangement is such that the various parts can be slipped into or out of place. The tongue and groove connection 22-23 between the drum cylinder 19 and its end plate 21 locks these members concentric, and the bolts 8 serve to hold the members laterally together. As shown, the heads 10 and 11 have slots 44 in which yieldable packing structures are inserted, whose construction and arrangement is

shown in Figs. 4, 5 and 6. The packing comprises an outer bearing ring 45 of suitable bearing material such as brass, an intermediate ring 46 of yieldable material such as felt, and an inner ring 47 possessing transverse elasticity. As best shown in Fig. 5, such elasticity may be produced by corrugating a metallic band, a spring of serpentine form capable of transverse expansion and compression. These packings will afford steam-tight bearing surfaces between the cylinder side walls 10 and 11 and the drum structure, and prevent passage of steam or gas should any escape from the working chambers. Similar packing 48 may be inserted between the flanges of the end structure and cylinder, and similar packing 49 may also be inserted in the slots 50 in the ends of cylinder 15 to engage with the plates 20 and 21 outside of the drum 19. I have also shown similar packing 51 inserted in the end plate 21 to engage with the hub 26, and similar packing 52 is also inserted in the inner ends of the hub 29 to be engaged by the drum plate 20. Similar packing is also provided for the various blades 35, each blade having the side and end channels 53 and 54 respectively, the right angled bearing plates 55 and 56 being jointed at 57 and being pressed outwardly by felt and spring layers arranged in the channels in the same manner as illustrated in Figs. 4, 5 and 6. Packing 58 is also provided in the rocking bearing members 39 for engaging with the blades, and packing 59 of these rocking members engage with the sides of the passageways 37. With all these packings it will be impossible for steam or gas to escape to the exterior of the engine, and the packings are yielding and the friction is reduced to a minimum.

A stuffing gland 60 may be provided for the outer end of the passageway 28 in the side structure 11, the stuffing material 61 being compressed by the gland against the sides of the passageway and the shaft to prevent leakage. At the other side a bushing 62 may be inserted in the pocket 63 around the shaft and its packing slots 64 filled with suitable packing material 65. In order to equalize the end thrust of the steam or gas pressure an equalizing vent 66 may be provided in the hub 26 to extend from the drum interior to the bushing 62. To equalize the pressure at opposite sides of the drum between the drum and cylinder walls outside of the packings 44 and 49 one or more equalizer passageways 67 may be provided, and to equalize the pressure in the spaces at opposite sides of the drum between the packings 44 and 52 vent passageways 68 and 69 are provided and these passageways could lead to atmosphere or could be connected together.

It can readily be seen that the engine 130

disclosed is of very simple and economical construction, there being few parts and such parts being adapted to be readily slipped into or out of place so that assembling and dismantling can be very readily accomplished. The packings keep the various members in accurate relative position during operation of the engine and also prevent leakage or circulation of steam or gas between the various parts. The ball bearings keep the drum structure accurately centered with reference to the housing sides so that the drum structure will rotate uniformly and freely and without friction.

I do not, of course, desire to be limited to the exact construction and arrangement shown and described, as changes and modifications are no doubt possible which would still come within the scope of the invention.

I claim:

1. In a rotary engine, the combination with a stationary housing comprising end structures and a central structure forming a cylinder, of a rotary drum structure in said housing having on one end thereof a laterally extending hollow hub, a hub extending inwardly from one end structure, an annular hub extending inwardly from the other end structure and surrounding said drum hub, annular bosses extending laterally from said drum structure and surrounding the hubs of said end structures, anti-friction bearings interposed between said bosses and hubs to mount said drum structure for rotation, a bearing boss forming an inward eccentric extension of one of said end structure hubs, a shaft extending through and secured to said drum hub and also extending through and journaled in said bearing boss, and piston blades journaled at their inner ends on said bearing boss and extending through slots in said drum structure.

2. In a rotary engine, the combination with a stationary housing comprising end structures and a central cylinder structure, of a rotary drum structure in said housing

having radial flanges overlapping the ends of said central cylindrical structure and having on one end thereof a laterally extending hollow hub, a hub extending inwardly from one end structure, an annular hub extending inwardly from the other end structure and surrounding said drum hub, annular bosses extending laterally from the opposite ends of said drum structure and surrounding the hubs of said end structures, anti-friction bearings interposed between said bosses and hubs to mount said drum structure for rotation, a bearing boss forming an inward eccentric extension of one of said end structure hubs, a shaft extending through and secured to said drum hub and having a reduced portion extending through and journaled in said bearing boss, and piston blades journaled at their inner ends on said bearing boss and extending through slots in said drum structure.

3. In a rotary engine, the combination with a stationary housing, of a drum structure therein, said housing comprising a central cylinder section and end sections secured together, hubs extending inwardly from said end sections and said drum structure being journaled on said hubs for rotation, said drum structure being sectional and the sections being provided with groove and tongue connection to lock them against relative diametral displacement, and means for locking said drum structure sections axially together.

4. In a rotary engine, the combination with a stationary housing, of a drum structure therein, said housing comprising a central section and end sections secured together, hubs extending inwardly from said end sections and said drum being journaled thereon for rotation, said drum structure being divided diametrically into sections, through bolts for locking the drum structure sections together axially, and dowel pins for alining the drum sections to facilitate insertion of the bolts.

JOHN D. CARROLL.
